Primary Examiner — Jack Reickel*Assistant Examiner* — Salamah Jordan(74) *Attorney, Agent, or Firm* — ArentFox Schiff LLP;
Joseph M. Maraia; Marlo S. Grolnic(57) **CLAIM**

The ornamental design for a cable training device, as shown and described.

DESCRIPTION

FIG. 1 is a perspective view of a cable training device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the Figures show particular elements of the cable training device and are included for illustrative purposes only and form no part of the claimed design.

1 Claim, 6 Drawing Sheets(56)
